(57) **CLAIM**

The ornamental design for a touch-sensitive control panel as shown and described.

DESCRIPTION

FIG. 1 is a bottom view of a touch-sensitive control panel in a first embodiment;

FIG. 2 is a front view thereof;

FIG. 3 is a left side view thereof;

FIG. 4 is a front perspective view thereof;

FIG. 5 is a right side view thereof;

FIG. 6 is a top view thereof;

FIG. 7 is a top view of a touch-sensitive control panel in a second embodiment;

FIG. 8 is a left side view thereof;

FIG. 9 is a front view thereof;

FIG. 10 is a right side view thereof;

FIG. 11 is a bottom view thereof;

FIG. 12 is a front perspective view thereof;

FIG. 13 is a right side view of a touch-sensitive control panel in a third embodiment;

FIG. 14 is a top view thereof;

FIG. 15 is a left side view thereof;

FIG. 16 is a front view thereof;

FIG. 17 is a front perspective view thereof; and,

FIG. 18 is a bottom view thereof.

In the drawings, the broken lines depict a portion of the touch sensitive control panel which form no part of the claim. The U.S. Trademark Reg. No. 5169087 for "ELEKTRONIKON" forming part of the claimed design is a registered trademark of ATLAS COPCO AIRPOWER, naamloze vennootschap.
